ATTORNEY

UNITED STATES PATENT OFFICE

CHARLES LORBER, OF BLOOMFIELD, NEW JERSEY

SWIVEL KEY PLATE

Application filed December 5, 1928. Serial No. 323,927.

This invention relates to key cases and has special reference to a hook suspension for key cases.

One important object of the invention is to improve the general construction of devices of this character.

A second important object of the invention is to provide improved means for connecting the key hook to the key plate used in devices of this character.

A third important object of the invention is to provide an improved arrangement of hook shank and supporting stirrup in devices of this character.

15 With the above and other objects in view as will be hereinafter apparent, the invention consists in general of certain novel details of construction and combinations of parts hereinafter fully described, illustrated in 20 the accompanying drawings and specifically claimed.

In the accompanying drawings like characters of reference indicate like parts in the several views, and:

25 Figure 1 is a face view of a key plate showing hooks suspended therefrom in accordance with this invention.

Figure 2 is a front view of one of the hooks of Figure 1 removed from the other parts.

30 Figure 3 is a plan view of the stirrup used in Figure 1 before bending to shape.

Figure 4 is an end view of the stirrup bent to shape.

Figure 5 is a view showing a modified 35 stirrup and hook connection.

Figure 6 is a side view of the hook of Figure 5 before being assembled with the stirrup.

40 Figure 7 is a view similar to Figure 3 but showing the stirrup of Figure 5.

Figure 8 is a second modification of the stirrup and hook connection.

Figure 9 is a side view of the hook shown 45 in Figure 8 before assembling.

Figure 10 is a view similar to Figure 3 but showing the stirrup of Figure 8.

Figure 11 is a view similar to Figure 10 but showing a fourth form of stirrup.

50 Figure 12 is a side view of a fourth form

of hook adapted to be used with certain of the stirrups shown herein.

Figure 13 is a view showing a fifth form of hook.

Figure 14 is a perspective view of a further modification of the stirrup.

Figure 15 is a view similar to Figure 3 but showing the modification of Figure 14.

Figure 16 is a view similar to Figure 8 showing the assembly of this last modification of the stirrup.

As shown in Figure 1 the hooks may either swing from the lower edge of a plate as in the full line position of said plate or may swing over the plate from the upper edge as in the dotted line position.

In the embodiments of the invention herein described there is employed a plate 10 adapted to be secured to the key case by suitable rivets, not shown, passing through rivet openings 11. This plate has fingers projecting from its lower edge in spaced relation and these fingers are bent to form eyes 12. In each of these eyes there is a stirrup which carries a suitable key supporting hook. In the form shown in Figures 1 to 4 this stirrup consists of a flat strip of metal 13 having at its ends opposed notches or slots 14 and the strip in use is bent so that the notched ends 14 overlap each other as at 15 in Figure 1.

In Figure 2 a form of hook is shown adapted for use with this type of stirrup and it will be noted that the hooks of Figures 12 and 13 may also be used with this stirrup. In the hook of Figure 2 there is the usual body 16 and shank 17 but this shank has a reduced neck portion 18 which is received in the notches 14, the upper end 19 of the shank being left in its natural size to form a head. Thus the hook is supported so it may swivel freely while the stirrup permits it to swing vertically and laterally as indicated by the dotted lines in Figure 1.

In Figures 5 to 7 the stirrup is formed from a strip 20 having a centrally disposed opening 21 wherethrough the shank 22 of a hook 23 is passed, the shank being upset as at 24 in Figure 5 to form a head. Preferably this shank is provided with a collar 25 to prevent

its slipping up in the stirrup and the stirrup is formed as shown in Figure 5 by bending to rectangular form with the ends 26 overlapping, these ends being held in the respective eye 12 of the plate.

In the form shown in Figures 8 to 10 the stirrup is made from a single strip 27 and is provided with openings 28 adjacent its ends which correspond to the slots 14 but in this instance a hook 29 having a plain straight shank 30 is passed through the alined holes or openings 28 after the stirrup is bent as in Figure 8 to have the ends overlap as at 31. This shank 30 is then stamped or offset to provide a head 32, being thus held in the stirrup which is carried in the usual manner in a respective eye 12. In Figure 11 there is a slight modification of the stirrup wherein it is made from a plate 33 having an opening 34 at one end and a slot 35 at the other. This form of stirrup can be assembled with the hook as in Figure 8. In Figure 12 there is shown a hook having a body 36 provided with a shank 37 on which is a preformed head 38 and the construction of Figure 13 is the same as in Figure 12 except that in Figure 13 there is provided a collar 39 below the head 38. These two forms may be used conveniently with the stirrup of Figure 3 or with the stirrup shown in Figures 14 and 15 wherein the stirrup is made from the usual strip 40 but is provided with semi-circular notches 41 at its ends and the strip is bent so that the notched ends lie in abutting alinement as shown at 42 in Figures 14 and 16, the latter figure showing the stirrup and hook assembled.

It will be obvious that in all of these forms the head on the shank is exposed to view so that any wearing of this head is readily detected.

The forms of stirrup herein shown are such that they may be provided by automatic machinery in great quantities at a low cost since the construction is of very simple character and at the same time this stirrup and swivel hook connection, in its various forms, makes for a very flexible connection between the keys and the key plate 10 so that the keys may be readily manipulated in any desired position.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a key holder, a hook supporting stir-

rup consisting of a single strip of metal of uniform width and thickness throughout bent to form a link and having at one end a hook shank receiving opening, the ends of said link being provided with overlapping cooperating shank receiving portions.

2. In a key holder, a hook supporting stirrup consisting of a single strip of metal of uniform width and thickness throughout bent to form a link and having at one end a hook shank receiving opening, the ends of said link being provided with overlapping cooperating shank receiving portions each having a shank receiving notch in its end.

3. In a key holder; a hook supporting stirrup consisting of a single strip of flat wire bent to form a link having the ends of the strip at right angles to the adjacent parts and one end overlapping the other and having its end abutting against the strip adjacent the remaining end of the strip, said ends being provided with opposed and registering notches for gripping a swivel hook shank.

In testimony whereof I affix my signature:

CHARLES LORBER.
